METHOD OF AND APPARATUS FOR PRODUCING TUFTED PRODUCT HAVING UNSEVERED AND SEVERED LOOPS

Joseph Kelly McCutchen, Ellijay, Ga.

Application April 10, 1956, Serial No. 577,240

15 Claims. (Cl. 112—79)

My invention relates to tufting machines and a method for producing tufted products.

An important object of the invention is to provide a tufting machine and method which is operable for producing severed and unsevered loops, in selected order, for producing a varied design.

A further object of the invention is to provide a machine and method embodying coacting loopers, one looper serving to produce the unsevered loops and the other looper serving to produce the severed loops when transferred thereto from the first looper.

A further object of the invention is to provide an apparatus and method which is relatively simple and reliable in operation.

Other objects and advantages of the invention will be apparent during the course of the following description.

In the accompanying drawings forming a part of this application and in which like numerals are employed to designate like parts throughout same,

Figure 1 is a side elevation, partly diagrammatic, and parts in section, of a machine embodying loopers and associated elements for practicing the method and showing the loopers in the opened position,

Figure 2 is a plan view of the looper for forming the unsevered loop,

Figure 3 is a side elevation of the same,

Figure 4 is an elevation of the opposite side of the looper,

Figure 4a is a horizontal section taken on line 4a—4a of Figure 4,

Figure 5 is a transverse vertical section taken on line 5—5 of Figure 4,

Figure 6 is a plan view of the looper for producing the severed loops,

Figure 7 is a side elevation of the same,

Figure 8 is an end elevation of the same,

Figures 9 to 12 inclusive are side elevations, partly diagrammatic, of the two loopers showing their operations for producing unsevered loops,

Figures 13 to 18 inclusive are side elevations, partly diagrammatic, showing the operations of the two loopers for producing an elongated unsevered loop which is transferred to the looper upon which it is subsequently severed, completed short unsevered loops which are not transferred to the other looper to be severed thereon, being also shown.

Figure 19 is a plan view of a section of fabric embodying my design.

Figure 20 is a vertical section taken on line 20—20 of Figure 19.

Figure 16a is a plan view of the loopers shown in Figure 16, the yarn being shown in horizontal section.

Attention is first called to Figure 1, wherein the numeral 25 designates a stationary frame, holding a horizontal top 26, having an opening formed therein to receive the reciprocating needle, carried by a needle bar, not shown, which is reciprocated by any conventional

2

means. The opening in the top 26 permits of the withdrawal of the formed loops, upon the feed of the fabric. Cooperating with the needle 27 is a presser foot 29. Work feed means includes rollers 30 and 31 mounted upon the frame 25 and the roller 31 is turned in the direction of the arrow, intermittently, to effect a step-by-step feed of the fabric or work 32. When the needle 27 is out of the fabric, the work 32 is fed a step and when the work is at rest, the needle passes through the work. This is the action of a conventional work feed for a sewing machine. The invention is not restricted to the precise form of work feed means shown, as I contemplate using feed dogs as illustrated in the patent to Baggett and Gordon, 2,143,678.

15 The numerals 33 and 34 designate horizontal rock shafts, arranged in suitable bearings, and these rock shafts are each turned in opposite directions by the conventional cam means. Rigidly mounted upon the rock shaft 33 is an upstanding crank or arm 35, having a severed loop forming looper 36 rigidly secured thereto. The looper 36 is generally horizontally arranged and includes a bill 37 having a downturned hook 38. Disposed opposite to the looper 36 is an unsevered loop forming looper 39, having a bill 40 free from the downturned hook. The looper 39 is pivoted at 41 in an opening 42 formed in an upstanding reciprocating supporting element, arm or crank 43, rigidly mounted upon the rock shaft 34. The upstanding supporting element has an upper portion, which upper portion faces upwardly 30 permanently. A retractile coil spring 44 is attached to the outer end of the looper 39 and serves to swing its inner end upwardly and hold the looper 39 against the stop wall 45, while the forward portion of the looper is spaced from the wall 46, which may be inclined, as shown. The outer end of the looper 39 is connected with a cable 47, passed about a pulley 48 mounted upon a fixed bracket 49. When the cable 47 is pulled downwardly in the direction of the arrow, Figure 1, the looper 39 is swung upon its pivot 41 with respect to the arm 40 or crank 43 and its free end or bill 40 is moved to the lowermost position, beneath its normal position. The cable 47 may be manually operated or it may be automatically operated. I contemplate embodying the invention in multiple needle machines, in which event a plurality of loopers 39 and cables 47 would be used, and the cables 47 would then be pulled and released by doby jacks.

45 The bill 37 of the looper 36, Figures 6 to 8, tapers toward its free end and is beveled at its free end, as indicated at 50, Figures 6 and 8, forming a thin edge 51 and the bevel continues throughout the hook 38. The hook 38 is bent laterally with respect to the bill 37, Figures 6 and 8. The hook 38 extends laterally beyond the side of the bill 37 which is next to the looper 39. 50 The looper 39 is provided upon its inner face next to the looper 36 with a transverse or vertical recess 52, Figures 2 to 4, disposed longitudinally outwardly of the bill 40 and this recess is adapted to receive the laterally bent hook 38 and the hook moves into, through, and 55 out of the recess 52. The inner end of the recess 52 beneath the bill is open, and this open end is generally vertical and arranged next to the looper 36, Figures 4 and 4a.

60 Coacting with the looper 36 is a blade or cutter 54, having shearing action with the bill 37 of the looper 36, and this blade or cutter is carried by a horizontal rock shaft 55, supported in suitable bearings. The rock shaft 55 is turned in timed order with respect to the looper 36 to sever the loop or loops upon the bill 37. 65 This cutting means is conventional and is similar to that shown in the Baggett and Gordon patent, 2,143,678,

but I also contemplate mounting the blade or cutter upon the looper 36.

The operation of the machine and the practice of the method is as follows:

I will first describe the production of unsevered loops, and the practice of the method is illustrated in Figures 9 to 12 inclusive. When the needle 27 is in the uppermost position and out of the fabric, Figure 9, the work is fed a step in the direction of the arrow and then brought to rest. When the needle 27 is in the uppermost position, the loopers 36 and 39 are both in the outer position, Figure 9. The needle 27 now moves downwardly and penetrates the work and when it reaches the lowermost position, the looper 39 moves inwardly and the bill 40 moves into the loop L and the looper 39 remains in this inner position when the needle 27 rises and stays in this inner position until the needle reaches its uppermost position, Figures 10 and 11. When the needle 27 moves to the lowermost position, Figure 10, the bill 40 has entered the loop, as described, and when the needle rises somewhat so that it is out of the way of the bill 37, then the bill 37, Figure 11, moves inwardly toward the path of travel of the needle and upon one side of the bill 40 and outwardly of and in close relation to the side S of the loop L. The hook 38 is now arranged below the bill 40, Figure 11, and the bottom of the loop L and hence the hook 38 and bill 37 cannot enter the loop formed upon the bill 40. The laterally bent hook 38 travels beneath the bill 40 and moves into the recess 52 through its inner open vertical end and when the loopers 36 and 39 are again moved to the open position, Figure 12, the hook 38 passes from the recess 52, and the bills 37 and 40 are separated. The hook 38 passes through the inner open vertical end of the recess 52 and through its open bottom. The hook 38 remained beneath the closed lower end of the loop L. The work is traveling to the right, Figure 12, and since the bill 40 has no downturned hook thereon, the loop L will slide from the free end of the bill 40, as it is fed with the fabric and will not be caught by the bill 37. This operation occurs when the spring 44 retains the looper in the raised position with respect to the crank or arm 43, Figure 1.

The arms or cranks 35 and 43 are swung toward each other and then from each other. When the needle 27 reaches the end of its upstroke, the looper 39 starts to move inwardly in timed order with respect to the needle so that the bill enters the loop while the needle is at the bottom of the downstroke or while it has just started to move up, Figure 10, and when the needle moves up a part of its upstroke, the looper 36 then moves to the inner position, Figure 11, but the bill 37 does not enter the loop since the hook 38 passes beneath the bottom of the loop. The cycle of operation shown in Figures 9 to 12 inclusive may be repeated any number of times and any corresponding number of unsevered loops formed in succession upon the bill 40 and pass therefrom and are not transferred to the bill 37 and hence remain unsevered. When the needle is approaching the top of its upstroke, the looper 39 moves outwardly and upwardly, before the looper 36 moves outwardly. The bill 40 moves into the loop L before the bill 37 is shifted to the inner position, and both bills 40 and 37 are in the inner overlapping position, when the needle is at the bottom of its down stroke.

The operation of the machine and the practice of the method for producing severed loops is shown in Figures 13, 14, 15, 16, 17 and 18. In Figure 13, the loopers 36 and 39 are in the outer positions and the needle is at the top of its upstroke. The looper 39 is now in the raised position with respect to the arm 43 and is held in this position by the spring 44. The needle 27 descends and passes through the work and when it reaches the end of its downstroke, the arm 43 swings the looper 39 inwardly so that its bill 40 enters the loop L, but the looper

36 is still in the outer position. After the bill 40 has entered the loop L, the cable 47 is pulled down and the bill 40 swung to the lowered position with respect to the arm 43 and looper 36 and pulls the loop L down a short distance, Figure 15. The cable 47 holds the bill 40 in the lowered position, Figure 16, and the looper 36 then moves inwardly and enters the loop L, since its hook 38 is laterally bent toward the looper 39, and will pass between the sides of the loop and the hook 38 will also move into the upper end of the recess 52 in the looper 39. After the bill 37 has thus entered the loop L, the cable 47 is released and the spring 44 returns the looper to the raised position and the bills 37 and 40 will again be in overlapping relation, Figure 17. As the needle continues to rise, the looper 39 moves outwardly and upwardly and the looper 36 also swings outwardly and its hook 38 passes from the inner open generally vertical end of the recess 52, Figure 18. The pulling and releasing of the looper 39 with respect to the arm 43 is of course timed with respect to the movement of the needle and any suitable means may be employed to pull the cable 47 downwardly, the spring 44 returning it to the raised position. The cable 47 may be connected with a dobby jack to be operated thereby, which would be the case where the invention is embodied in a multiple needle machine, but the cable 47 may be manually operated.

It is thus seen that unsevered loops are formed upon the bill 40 of the looper 39 and these unsevered loops are transferred to the bill 37 of the looper 36, and are severed on the looper 37 by the blade 54. In this manner, any number of severed loops may be formed in succession. The machine can also be operated for forming alternate severed and unsevered loops.

With respect to Figures 13 to 18 inclusive, it is to be noted that a plurality of short unsevered loops have been formed, in accordance with the operation as explained in Figures 9 to 12 inclusive. In Figure 15, the long unsevered loop is formed, by swinging the bill of the looper 39 downwardly. When the bill 37 of the looper 36 moves forwardly, it moves into the elongated loop and also enters the top of the recess 52, Figures 2 and 4. When the looper 39 is returned to the horizontal position, extension 38, Figure 7, is beneath the bill 40. The long loop is now applied to the looper 37 and when the looper 37 is moved to the open position, Figure 18, the long loop remains upon the looper 37 and the extension 38 passes from the open side of the recess 52, Figures 4 and 4a. The long loop and any subsequent long loops which are entered by the looper 37 remain upon the looper 37 and are subsequently severed, as these long loops are fed toward the closed end of the looper 37, as is well known in the art.

It is to be understood that the form of the machine herewith shown and described is to be taken as a preferred embodiment of the same, and that various changes in the shape, size and arrangement of parts may be resorted to, and that changes may be made in the order of the steps of the method, without departing from the spirit of my invention or the scope of the subjoined claims.

Having thus described my invention, I claim:

1. A method of producing unsevered and severed loops upon a fabric, comprising forming in succession a plurality of loops upon the fabric and applying each loop when formed upon a looper, removing each loop from the looper to form an unsevered loop, forming in succession a plurality of loops upon the fabric, applying each of the last-named loops when formed upon the same looper upon which the first-named loops were applied, transferring each last-named loop from the first looper to a second looper, and then severing each transferred loop while upon the second looper.

2. A method of producing unsevered and severed loops upon a fabric, comprising forming in succession a plurality of loops upon the fabric, moving a first looper into

each loop when formed, removing each loop from the first looper to form an unsevered loop, forming in succession a plurality of second loops upon the fabric, moving the first looper into each of the second loops when formed, transferring each second loop from the first looper to a second looper, and then severing each transferred second loop while it is upon the second looper.

3. A method of producing unsevered and severed loops upon a fabric, comprising sewing a loop in the fabric and applying the loop to a first looper, removing the loop from the first looper to form an unsevered loop, sewing a second loop in the fabric and applying the second loop upon the first looper, transferring the second loop from the first looper to a second looper, and then severing the transferred second loop while it is upon the second looper.

4. A method of producing unsevered and severed loops upon a fabric, comprising forming a first loop upon the fabric and moving a first looper into the first loop, removing the first loop from the first looper to form an unsevered loop, forming a second loop upon the fabric and moving the first looper into the second loop, transferring the second loop from the first looper to a second looper, and then severing the transferred second loop while it is upon the second looper.

5. A method of producing unsevered and severed loops upon a fabric, comprising sewing a first loop in the fabric, moving a first looper toward the first loop and causing the bill of such first looper to enter the first loop, moving a second looper toward the first loop while it is held upon the bill of the first looper and causing the free end of the bill of the second looper to travel beneath the first loop held upon the bill of the first looper so that the bill of the second looper will not enter said first loop, effecting a relative opening movement between the loopers and causing the first loop to pass from the bill of the first looper to form an unsevered loop, sewing a second loop in the fabric and moving the bill of the first looper into the second loop, moving the second looper toward the second loop while it is held upon the bill of the first looper and causing the free end of the bill of the second looper to pass above the bill of the first looper and enter the second loop upon the bill of the first looper, and then effecting a relative opening movement between said loopers which causes the second loop to be transferred to the bill of the second looper, and then severing the second loop while on the bill of the second looper.

6. A method of producing unsevered and severed loops upon a fabric, comprising sewing a first loop in the fabric, feeding the fabric a step after sewing such loop, arranging a first looper near the fabric and having the bill of the first looper extending toward the direction of the feed of the fabric and moving the first looper toward the first loop and causing the bill of such first looper to enter the first loop, arranging a second looper near such fabric and causing the bill of the second looper to face in an opposite direction to the feed of the fabric and moving the second looper toward the first loop while it is held upon the bill of the first looper and causing the free end of the bill of the second looper to travel beneath the first loop held upon the bill of the first looper so that the bill of the second looper will not enter said first loop, effecting a relative opening movement between the loopers and causing the first loop to pass from the bill of the first looper to form an unsevered loop, sewing a second loop in the fabric and moving the bill of the first looper into the second loop, moving the second looper toward the second loop while it is held upon the bill of the first looper and causing the free end of the bill of the second looper to pass above the bill of the first looper and enter the second loop upon the bill of the first looper, then effecting a relative opening movement between said loopers and thereby causing the second loop to be transferred to the bill of the second looper, and then severing the second loop while on the bill of the second looper.

7. A method of producing unsevered and severed loops upon a fabric, comprising sewing in succession loops, feeding the fabric in one direction a step after each loop has been formed, holding a first looper so that its bill faces in the direction of the feed of the fabric and moving the first looper so that its bill enters each loop in succession, holding a second looper so that its bill faces in an opposite direction to the feed of the fabric and moving the second looper toward the first looper in succession and causing the bill of the second looper to remain exteriorly of certain loops held upon the bill of the first looper, moving the second looper toward the first looper and then causing the bill of the second looper to enter certain loops arranged upon the bill of the first looper and thereby transferring such loops to the bill of the second looper, and then severing in succession loops held upon the bill of the second looper.

8. A method of producing unsevered and severed loops upon a fabric, comprising sewing loops in the fabric, feeding the fabric in one direction during the sewing operation, holding a first looper so that its bill faces in the direction of feed of the fabric, holding a second looper near and opposite the first looper and having its bill facing in the opposite direction to the feed of the fabric, reciprocating the first looper in a path of travel at a fixed elevation and causing the bill of the first looper to enter certain of the loops, reciprocating the second looper in a path of travel at a fixed elevation and causing the free end of the bill of the second looper to pass beneath and exteriorly of the loop upon the bill of the first looper and thereby causing the loop upon the bill of the first looper to pass therefrom without passing upon the bill of the second looper, then moving the first looper in the fixed path of travel and causing its bill to enter the loop, moving the bill of the first looper downwardly when such bill is in the loop, then moving the second looper in the fixed path of travel toward the first looper and causing the bill of the second looper to pass above the bill of the first looper which is then in the lowered position, then returning the bill of the first looper to the raised position, and then moving the first and second loopers from each other whereby the loop is transferred to the second looper, and then severing the loop upon the second looper.

9. In a tufting machine, a work support, a work feed means, a reciprocatory needle bar carrying a needle to sew loops in the work, a looper arranged near the work support and including a bill to enter the loops, said looper having an upstanding recess upon one side arranged behind the bill, said recess having a top and its side next to the bill open, a pivoted reciprocatory support, means to pivotally mount the looper upon the support, means to move the looper with respect to the support so that the elevation of its bill is varied with relation to said support, a second looper arranged opposite the first looper and including a bill having a depending hook at its free end, the hook being laterally offset with respect to the bill in a direction toward said recess, and a pivoted reciprocatory support carrying the second looper, and means to sever the loops upon the second looper.

10. In a tufting machine, as a sub-combination, a looper having a bill and an upstanding recess arranged rearwardly of the bill, said recess extending downwardly below the bill, the top of the recess and its forward side being open, and a coacting looper including a bill provided with a downwardly extending hook at its free end, said hook being offset laterally toward the recess.

11. In a tufting machine, a work support, work feed means, a reciprocatory needle bar carrying a needle to sew loops in the work, a looper arranged near the work support and including a bill to enter the loops, said looper having an upstanding recess upon one side and arranged behind the bill, said recess having its top and forward side open, a reciprocatory support, means pivotally mounting the looper upon the support, a spring

to hold the looper in one position with respect to the support, means connected with the pivoted looper to swing the pivoted looper to an adjusted position with relation to the support, a second looper arranged near and opposite the first looper and including a bill having a depending hook at its free end, the hook being extended laterally with respect to the bill toward said recess, a reciprocatory support carrying the second looper, and means to sever loops upon the second looper.

12. In a tufting machine, a work support, work feed means, a first upstanding arm arranged beneath the work support, means for pivotally supporting the first upstanding arm and reciprocating the same in a substantially vertical plane, a first looper facing in an opposite direction to the work feed and mounted upon the upper end of said first arm and movable with the first arm and including a bill provided near its free end with a laterally extending hook, a second upstanding arm arranged opposite to the first upstanding arm, means for pivotally supporting and reciprocating the second upstanding arm in a substantially vertical plane, a second looper pivotally mounted upon the upper end of the second arm and provided with a bill facing in the direction of the work feed, the second bill being free from a hook so that the loop applied to the second bill may be removed from the same by the movement of the loop with the work, the second looper being provided with an upstanding recess arranged near and rearwardly of the second bill, said recess extending transversely of the looper and having its upper end open and its forward side open, said recess being adapted to receive said hook, means to hold the second looper in a position with relation to the second arm to raise the free end of its bill so that the hook of the first looper will travel beneath the second bill when said loopers are moved toward each other and will not enter the loop on the second looper, and means to move the second looper with respect to the second arm to lower the free end of the second bill so that the hook of the first looper will pass above the bill of the second looper and enter the loop upon the second looper when the loopers are moved toward each other.

13. In a tufting machine, a work support, work feed means, means arranged above the work support and including a needle to sew loops in the work, an upstanding reciprocatory supporting element mounted beneath the work support and including an upper portion arranged near the work support and moving longitudinally of the work support, said upper portion facing upwardly permanently, means to reciprocate the supporting element, a looper including a bill to enter the loops, means to adjustably mount the looper upon said upper portion so that the looper travels with the upper portion and is permanently movable with relation to said upper portion for raising and lowering said bill, means separate from the reciprocating means and connected with the looper

to move the same with relation to said upper portion, a second looper arranged beneath the work support near and opposite to the first looper and including a bill having a free end, means to support and reciprocate the second looper, and means to sever loops upon the second looper.

14. In a tufting machine, a work support, work feed means, means arranged above the work support and including a needle to sew loops in the work, an upstanding vertically swinging arm arranged beneath the work support and including an upper portion which is arranged permanently near and beneath the work support, means to support and reciprocate the upstanding arm so that the upper portion of the arm moves longitudinally of the work support, a looper including a bill to enter the loops, means to adjustably mount the looper upon the upper portion so that the looper travels with the upper portion and is permanently movable with relation to said upper portion for raising and lowering said bill, means separate from the supporting and reciprocating means and connected with the looper to move the same with relation to said upper portion, a second looper arranged near and beneath the work support and opposite to the first looper and including a bill having a free end, means to support and reciprocate the second looper, and means to sever loops upon the second looper.

15. In a tufting machine, a work support, work feed means, means arranged above the work support including a reciprocatory needle to sew loops in the work, a looper arranged beneath and near the work support and including a bill facing in a direction opposite to the feed of the work and having a downwardly extending hook near its free end, means to support and reciprocate the looper, means to enter the loops formed by the needle and transfer the same to the first-named looper, the last-named means including a reciprocatory support, a looper facing in the same direction with the feed of the work, means to adjustably mount the last-named looper upon said reciprocatory support so that the last-named looper is permanently movable with relation to said reciprocatory support to vary the elevation of the inner end of the last-named looper, means connected with the last-named looper to move it with relation to said support, and means to sever the loops transferred to the first-named looper.
